(57) **CLAIM**

The ornamental design for a tool handle, as shown and described.

DESCRIPTION

FIG. 1 is a perspective view of a tool handle in accordance with the invention;

FIG. 2 is a first side elevational view of the handle;

FIG. 3 is a second side elevational view of the handle;

FIG. 4 is a top plan view of the handle;

FIG. 5 is a bottom plan view of the handle;

FIG. 6 is a front elevational view of the handle;

FIG. 7 is a rear elevational view of the handle;

FIG. 8 is a perspective view of a modified tool handle in accordance with the invention;

FIG. 9 is a first side elevational view of the modified tool handle;

FIG. 10 is a second side elevational view of the modified handle;

FIG. 11 is a top plan view of the modified handle;

FIG. 12 is a bottom plan view of the modified handle;

FIG. 13 is a front elevational view of the modified handle; and,

FIG. 14 is a rear elevational view of the modified handle.

The lines shown on the surface of the drawings are an element of the design and are not shading.
